Loren C. Bond INVENTOR
By Alexander Lowell ATTORNEY.

UNITED STATES PATENT OFFICE.

LOREN C. BOND, OF WASHINGTON, DISTRICT OF COLUMBIA.

WEATHER STRIP FOR DOORS AND WINDOWS.

1,407,921.

Specification of Letters Patent. Patented Feb. 28, 1922.

Application filed February 12, 1921. Serial No. 444,445.

To all whom it may concern:

Be it known that I, LOREN C. BOND, a citizen of the United States, residing at Washington, in the District of Columbia, have invented certain new and useful Improvements in Weather Strips for Doors and Windows; and I hereby declare that the following is a full, clear, and exact description thereof, reference being had to the accompanying drawings, which form part of this specification.

This invention relates to so called weather strips especially adapted to be used on doors and windows for the purpose of excluding air, dust and moisture, and its object is to provide a substantial, simple and cheap device of this nature; which may be manufactured inexpensively, can be easily attached to a door, window or transom; will be attractive in appearance; easy to keep in repair; and will work satisfactorily even should the door warp from sunshine and moisture.

My novel weather strip consists essentially of two longitudinal members preferably formed of sheet metal bent into proper form, as hereinafter explained, and connected together by a hinge member preferably formed of fabric and united to the metal members in a manner hereinafter explained, and a packing or sealing member united to the lower metal member.

Minor objects of the invention are to form the longitudinal members of metal so curved and formed as to be very rigid; to provide a hinge member preferably of fabric or other suitable material connected to the longitudinal members in such a way as to permit swinging and also, if required, a slight end-wise movement of the lower member with respect to the upper member; to make the hinge connection between these members such that the members will be stiffened thereby; to secure a packing member of felt or other suitable material to the lower member in such manner as to render the weather strip impervious to air and moisture when closed; and to utilize the packing retaining device to stiffen the lower member.

I will explain the invention with reference to the accompanying drawings in which:

Figure 1 is a front view of the complete weather strip as applied to a door.

Fig. 2 is an enlarged sectional view thereof.

Fig. 3 is an enlarged detail section on the line 3—3 Fig. 1.

Fig. 4 is an enlarged section on line 4—4 Fig. 1.

As shown, the weather strip comprises an upper attaching member 1 and a lower closing or sealing member 2. The upper member is preferably made of a longitudinal strip of sheet metal having an outer part 1^a preferably bent transversely to approximately the form shown in Figs. 2 and 4. From the lower portion of part 1^a the strip is bent inwardly upon itself as at 1^b, and at the inner end of part 1^b the strip is again bent upon itself to form a loop 1^c.

At the inner end of the loop 1^c the strip is again bent reversely upon itself as at 1^d to form a retainer for one edge or side of the hinge member 4 hereinafter described.

The member 1 may be attached to the door D, or other object to which the strip is to be applied, by means of screws 3 extending through suitable openings in the part 1^a as shown in Figs. 1 and 2, and when so attached the bend of loop 1^c lies close to the door or other object to which the member 1 is attached.

The lower member 2 is also preferably formed of a longitudinal strip of sheet metal and curved transversely as shown in Figs. 2 and 4, and projects beyond and below the member 1 as shown. The upper edge of the strip forming member 2 is preferably bent reversely inwardly upon itself to form a longitudinal loop 2^a which loop abuts against the loop 1^c and close against the door D. Beyond and adjacent the loop 2^a the strip is again reversely bent upon itself as at 2^b to form a retainer for the lower edge of the hinge member 4. The lower part of the member 2 is inwardly bent upon itself to form a lower loop 2^c, and at the inner edge of the loop 2^c the strip is again bent upon itself to form a reverse loop 2^d which serves as a retainer for the sealing strip 5 hereinafter referred to.

The members 1 and 2 may be made or cut of any desired length and when properly cut they may be provided with end plates or closures 1^f and 2^f if desired to make a neater appearance when the door is open.

The hinge member 4 is preferably formed of fabric, but may be of other suitable material. As shown the upper edge of this hinge member is placed within the bend 1^a of member 1 and is secured therein by means of a wire 4^a and after the fabric and wire are inserted in the loop 1^c this loop

may be compressed, by any suitable tool, so as to bind the wire 4^a and the edge of the hinge fabric securely therein as indicated in Figs. 2 and 4.

- 5 The lower edge of the hinge member 4 is placed within the loop 2^b of member 2 and is retained therein by a wire 4^b and after the fabric and wire are inserted in the loop 2^b said loop may be tightly closed upon 10 the fabric and wire therein, by any suitable tool, so as to bind wire 4^b and the fabric therein.

- The sealing strip 5 may be made of felt or other suitable material adapted to make 15 a flexible yielding contact between the member 2 and the door sill S when the door is closed. The upper end of this sealing member 5 may be secured in the loop 2^a by a wire 5^a, see Figs. 2-4, and the loop 2^a 20 can be compressed upon the wire and fabric to securely fasten the same in position.

- The jamb 6 of the door may be cut out as indicated at 6^a in Fig. 3, so as to engage the adjacent end of member 2, and cause member 2 to swing inwardly and press the sealing member 5 against the sill S as and when the door is closed. The means 6^a in jamb 6^b may be provided with a metal wear plate 6^c as indicated in Fig. 3.

- 30 I preferably provide a spring for normally swinging the lower member 2 slightly upwardly so that it will not drag on the sill S when the door is being opened or closed. As shown in Fig. 3 a coil spring 7 is hung 35 on a keeper on one of the end plates 2^c, one end of the spring bearing against the end plate and the other end being attached to the door D, the spring being so arranged that it will normally tend to swing the member 2 upward on hinge 4 when the door is open. Any other suitable or preferred kind of spring could be used.

- From the foregoing description the utility, 45 simplicity and usability of the device will be obvious. The members 1 and 2 can be made in any desired length and then cut to fit the door, window or other object to which the strip is to be applied. The hinge member and sealing member can also be cut to corresponding lengths, and then the parts can be readily connected together in the manner described and applied to the door or other object; no special tools being required either for assembling the strip or applying the 55 strip to a door, etc.

I claim:

1. A weather strip comprising upper and lower members, the upper member having a part adapted to be attached to a door and 60 an inwardly projecting part extending from the lower portion of the top part toward the door and having a hinge member retaining loop at the inner edge of this inwardly projecting part; and the lower member being adapted to be placed beneath the

upper member and having a hinge member engaging loop on its upper part; and a hinge member having its upper part engaged with the hinge retaining loop of the upper member and its lower part engaged with the hinge retaining loop of the lower member. 70

2. In a weather strip as set forth in claim 1, wires inserted in the hinge retaining loops of the upper and lower members to fasten 75 the hinge member therein and also stiffen said upper and lower members.

3. A weather strip comprising upper and lower members; the upper member having a top part adapted to be attached to a door and an inwardly projecting part extending 80 from the lower edge of the top part toward the door, and a hinge member retaining loop at the inner edge of this lower part; the lower member being adapted to be placed beneath the upper member, having a hinge member engaging loop at its upper edge and a sealing member engaging loop on its lower edge; with a hinge member having its upper part engaged with the hinge retaining loop of the upper member and its lower 85 part engaged with the hinge retaining loop on the lower member.

4. In a weather strip as set forth in claim 3, wires inserted in the hinge retaining members of the upper and lower members to fasten 95 the hinge member therein and stiffen said upper and lower members.

5. A weather strip comprising upper and lower members, the upper member being formed of a metal strip bent to form a top 100 portion adapted to be attached to a door, and again bent at the lower part of said top part to form an inwardly projecting part, and again bent at the inner edge of said inwardly projecting part to form a hinge 105 member retaining loop; the lower member being formed of a metal strip bent at its top to form a member engaging loop; a sealing member attached to the lower part of the 110 lower member; and a hinge member having its upper part engaged with the hinge retaining loop on the upper member and its lower part engaged with the hinge retaining loop on the lower member.

6. In a weather strip as set forth in claim 415 5, wires inserted in the hinge retaining loop of the upper and lower members to fasten the hinge member therein and stiffen said upper and lower members.

7. A weather strip comprising upper and lower members, the upper member being formed of a metal strip bent to form a top portion adapted to be attached to a door, and again bent at the lower part of said top part to form an inwardly projecting part, and again bent at the inner edge of said inwardly projecting part to form a hinge member retaining loop; the lower member being formed of a metal strip bent at its top to 125 form a member engaging loop and at its 130

bottom to form a sealing member engaging loop; a hinge member having its upper part engaged with the hinge retaining loop of the upper member and its lower part engaged with the hinge retaining loop of the lower member; and a sealing strip engaged with the lower loop of the lower member.

5 8. In a weather strip as set forth in claim

7, wires inserted in the loops of the upper and lower members to fasten the hinge member and sealing strip therein; and to stiffen 10 said upper and lower members.

In testimony that I claim the foregoing as my own, I affix my signature.

LOREN C. BOND.
